Primary Examiner — Kevin Rudzinski*Assistant Examiner* — Sean D Lough(74) *Attorney, Agent, or Firm* — Paul F. Donovan(57) **CLAIM**

The ornamental design for a reflector housing, as shown and described.

DESCRIPTION

FIG. 1 is a perspective view of the reflector housing showing the new design;

FIG. 2 is a top view thereof;

FIG. 3 is a bottom view thereof;

FIG. 4 is a back view thereof;

FIG. 5 is a front view thereof;

FIG. 6 is a left side view thereof; and,

FIG. 7 is a right side view thereof.

The broken lines (where present) in all FIGS. illustrate portions of the reflector housing that form no part of the claimed design.
